(57) **CLAIM**

The ornamental design for a multi-picture frame assembly,
as shown and described.

DESCRIPTION

FIG. 1 is a front view of a multi-picture frame assembly
showing my new design;

FIG. 2 is a top view thereof;

FIG. 3 is a rear view thereof; and,

FIG. 4 is a right side view thereof.

The left side view is a mirror image of the right side view.
The bottom view is a mirror image of the top view.
The broken line are for illustrative purposes only and form
no part of the claimed design.
